UNITED STATES PATENT OFFICE.

JESSE B. McAFFEE, ELLERY D. BENTON, AND MILTON K. DAVIS, OF DALLAS, TEXAS.

DESIGN FOR A PHYSICIAN'S TRAFFIC-SIGNAL.

57,697.

Specification for Design.

Patented Apr. 26, 1921.

Application filed October 11, 1920. Serial No. 416,323. Term of patent 3½ years.

To all whom it may concern:

Be it known that we, JESSE B. McAFFEE, ELLERY D. BENTON, and MILTON K. DAVIS, residing, respectively, at Dallas, Dallas county, Texas, have invented a new, original, and ornamental Design for a Physician's Traffic-Signal, of which the following is a specification, reference being had to the accompanying drawing, forming part hereof.

Figure 1 is a face view of our new design, and

Fig. 2 is an edge view thereof, the cross being lined to indicate blue, but is intended to represent any color with the exception of red.

We claim:

The design for a physician's traffic signal as shown.
